(57) **CLAIM**

The ornamental design for a solar spotlight, as shown and described.

DESCRIPTION

FIG. 1 is a perspective view of a solar spotlight showing my new design;

FIG. 2 is a front view thereof;

FIG. 3 is a back view thereof;

FIG. 4 is a left view thereof;

FIG. 5 is a right view thereof;

FIG. 6 is an enlarged top view thereof;

FIG. 7 is an enlarged bottom view thereof;

FIG. 8 is a solar spotlight shown in an alternate configuration of use;

FIG. 9 is a solar spotlight as shown in FIG. 1, shown in an environment of use;

FIG. 10 is an enlarged view of the encircled area 10 of FIG. 1;

FIG. 11 is an enlarged view of the encircled area 11 of FIG. 3; and,

FIG. 12 is an enlarged view of the encircled area 12 of FIG. 3.

The broken lines shown in FIGS. 1, 3, 4, 5, 7, 8, 11, 12 illustrate portions of the solar spotlight that form no part of the claimed design. The additional broken lines annotating the detail views in FIGS. 1, 3, 10, 11 and 12 are for illustrative purposes and form no part thereof. The broken lines shown in FIG. 9 are directed to environment and are for illustrative purposes only and form no part of the claimed design.

1 Claim, 12 Drawing Sheets
